A. A. WEST

HAIR CURLER OR WAVER

Filed Jan. 31, 1923

INVENTOR
AUGUSTUS ALBERT WEST

BY
W. W. Williamson
ATTORNEY

UNITED STATES PATENT OFFICE.

AUGUSTUS ALBERT WEST, OF PHILADELPHIA, PENNSYLVANIA.

HAIR CURLER OR WAVER.

Application filed January 31, 1923. Serial No. 615,975.

To all whom it may concern:

Be it known that I, AUGUSTUS ALBERT WEST, a citizen of the United States, residing at 46 East Willow Grove Avenue, Philadelphia, in the county of Philadelphia and State of Pennsylvania, have invented new and useful Improvements in a Hair Curler or Waver, of which the following is a specification.

10 My invention relates to new, useful and important improvements in a hair curler or waver, and has for its primary object to provide means for preventing the clamping member from obstructing the winding of hair upon the body member. In my experiments I have used metal, celluloid and fiber, tubular bodies of circular, square and oval formation while the clamping member has been made of flat spring brass, steel and celluloid and also of round wire bent to form parallel strands as will be hereinafter set forth.

Another object of the invention is to provide a hollow body having a restricted opening at each end and a clamping member loosely and slidably connected with the body whereby it may be slid thereinto or clamped on the outside thereof.

With these ends in view, this invention 30 consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawing forming a part of this application, 40 in which:—

Fig. 1, is a side elevation of a hair curler or waver embodying my invention with the clamping member closed or clamped outside of the body as when holding hair.

45 Fig. 2, is a similar view with the clamping member inside of the body.

Fig. 3, is likewise a similar view with the clamping member pulled out ready to be thrown over for clamping, as shown in 50 Fig. 1.

Fig. 4, is an enlarged longitudinal sectional view of the device.

Fig. 5, is an enlarged view of the locking end of the body member.

Fig. 6, is a similar view of the hinge end 55 thereof.

Fig. 7, is a side elevation on a reduced scale of the curler or waver showing the manner in which the hair is wound thereon and illustrating how the clamping member 60 is positioned out of the way of the fingers when wrapping the hair on the device.

Fig. 8, is a plan or face view of the metal blank from which the body member is formed.

Fig. 9, is a plan view of the flat metal clamping member.

Fig. 10, is a plan view of the round wire clamping member which may be used in place of the one shown in Fig. 9.

In carrying out my invention as here embodied, 1 represents a resilient clamping member preferably formed of thin sheet metal such as brass and at one end is formed the locking hook 3 while the other end is 75 curved, bent or coiled to form an eye as at 7 for the reception of the axle 5 which may be formed of wire or a suitable equivalent.

If found desirable a clamping member 2, Fig. 10, may be used in place of the one 80 above described and said clamping member 2 is formed of round wire folded upon itself to provide two parallel strands and the ends of these strands are coiled or bent to form eyes 8 for the reception of the axle 6 the 85 same as that designated by the numeral 5. The doubled or folded end is bent to produce a locking hook 4 for the same purpose as the hook 3.

The hollow body member 9 has the ends 90 10 and 11, at the hinge end of the device, bent inward at right angles to partially form the restricted opening through which the clamping member projects to act as stops for the axle carried by the clamping 95 member to prevent the accidental withdrawal of the latter. The projections or extensions 12 and 13 on the same end of the body are likewise bent inward at right angles over the parts 10 and 11 while the por- 100

tion 14 is bent inward or downward to meet the parts 10 and 11 thus completing the formation of the restricted opening shown in Fig. 6.

5 The extension 15 acts as the catch for the clamping member, as plainly shown in Fig. 4, and this is preferably, slightly bent inward or downward with the side edges bent inward therefrom at substantially right angles to form flanges 18 and 19 which prevent the accidental sidewise displacement of the clamping member. The lugs or projections 16 and 17 are afterwards bent inward to partially close the locking end of the body.

10 To assemble my device the clamping member, completely formed with the axle attached, is inserted in the body by pushing the hook end through the locking end of said body prior to bending the projections 16 and 17 and after the hook end of the clamping member emerges from the hinge end of the body said projections 16 and 17 as well as the parts 12 and 13 are bent into 15 position, it being understood that the balance of the hollow body have been previously formed.

15 The clamping member is now locked into the body member it is slidable and adjustable so that it may be withdrawn until the axle engages the parts 10 and 11 or it may be reinstated in said body by moving it to a position substantially equal to that shown in Fig. 3 and then sliding the same longitudinally as will be obvious.

20 It is common practice to make hair curlers or wavers three inches long and with the clamping member extended the curler measures approximately six inches or said clamping member may extend out from the body at an angle thereto thereby increasing the size in another direction so that by comparison the improvement in my device becomes apparent because, for waving or curling the hair, it is necessary or desirable in 25 using any kind of waver to hold the same close to the head while the hair is wrapped thereon which is practically impossible, so far as I am aware, in devices of this character constructed in accordance with present day methods. In my invention the clamping arm is out of the way being encased within the body member, hence the hair may be wrapped on the body without the clamp- 30 ing arm interfering with the operations.

35 To wave the hair it is wrapped on the device starting from the center of the body.

40 The final operation in the use of my device is the same as in common practice wherein, after the hair has been wrapped on the body member the clamping member is bent over and held in place by engaging the hook with the catch 15 which is accomplished by giving a sidewise movement of the clamp-

45 ing member so that the nose of the hook rides under one of the flanges 18 or 19.

50 Another advantage of my device is in the slidable tension of the end 20 of the clamping member as a large quantity of hair will draw the axle of said clamping member toward the extension 14 along the square retaining ends or projections 10 and 11 which action to the best of my knowledge is novel in my invention. There is also a slidable tension of the clamping member at the hook 55 end in its engagement with the catch 15. The usual bowing of the clamping member, when a quantity of hair is used, is common with my device and similar curlers.

60 Modifications within the scope of the appended claims may be made without departing from the principle or sacrificing the advantages of this invention.

Having thus fully described my invention, what I claim as new and useful is:—

65 1. A hair curler having a clamping member attached to an adjustable and disappearing axle, and a hollow body member capable of enclosing the clamping member.

70 2. As an article of manufacture, a hair curler consisting of a hollow body and a clamping member slidably connected with said body for insertion in said body or clamping on the exterior thereof.

75 3. A hair curler comprising a hollow body, a clamping member having means at one end for detachable connection with said body and having means at its other end for hinged and slidable connection with said body, said clamping member adapted to be inserted in the body from the hinged end when the first named end is disengaged from the body.

80 4. A hollow body having a restricted opening at one end and provided with a catch at the opposite end, and a clamping member slidably connected with the body and insertible therein through the restricted opening, said clamping member having a hook for coaction with the catch on the body.

85 5. A hollow body having a restricted opening at one end and provided with a catch at the opposite end, a clamping member projecting through the restricted opening and slidable bodily within the body, so as to be completely housed said member having a hook at one end for coaction with the catch on the body, and means at the other end to permit of a hinged action of the clamping member relative to the body and to prevent the accidental displacement of the clamping member.

90 6. A hollow body having a restricted opening at one end and provided with a catch at the opposite end, a clamping member projecting through the restricted opening and adapted to be housed within the

body, said member having a hook at one end for coaction with the catch on the body, and an axle carried by the opposite end of the clamping member for engagement with the 5 walls of the body in the locality of the restricted opening to prevent the accidental displacement of said clamping member.

7. A hair curler including a hollow body, and a stiff clamping member slidale within 10 said body.

8. A hair curler comprising two members one of which telescopes within the other, said members being provided with coacting means whereby one of the members may be clamped on the outside of the other without 15 detachment when withdrawn from said other member.

In testimony whereof, I have hereunto affixed my signature.

AUGUSTUS ALBERT WEST.
